PROCESS FOR CRACKING AND POLYMERIZING HYDROCARBONS

Philip Subkow, Los Angeles, Earle W. Gard, Palos Verdes Estates, and Robert E. Haylett, Long Beach, Calif., assignors to Union Oil Company of California, Los Angeles, Calif., a corporation of California

Application October 29, 1935, Serial No. 47,238

3 Claims. (Cl. 196—10)

This invention relates to process for the formation of high anti-knock gasoline and particularly to processes for the conversion of low anti-knock gasoline and kindred fractions and the conversion of normally gaseous petroleum fractions into high anti-knock gasoline. The low anti-knock gasoline fractions are treated by modification of the process known as "reforming" which utilizes recombining and polymerizing reactions as well as decomposing reactions. The treatment of the normally gaseous hydrocarbons (and in some instances the low anti-knock gasoline) involves the building up of higher molecular weight hydrocarbons of high anti-knock quality by dehydrogenation accompanied by "polymerization" or "synthesis" and by molecular re-arrangement known as "isomerization." The process also involves the conversion of high molecular weight liquid petroleum fractions into lower molecular weight hydrocarbons by the processes known as "cracking," "dehydrogenating" and "reforming." The invention involves further the production of high anti-knock gasolines from liquid fractions as above mentioned while in contact with the normally gaseous fractions above mentioned by a combination of the processes for the conversion of the mentioned liquids and gases.

The conventional process for the reforming of gasoline consists in subjecting gasoline, kerosene or gas oil, preferably in vaporous form, to high temperatures under conditions whereby the stock is converted from one having low anti-knock properties to one in the gasoline range having high anti-knock properties. The gasoline is then separated from the fixed gases and normally gaseous hydrocarbons to yield a stabilized reformed gasoline. This process for the formation of high iso-octane number material may be visualized as proceeding through cracking, dehydrogenating and isomerizing reactions which yield as an intermediate or by-product, low molecular weight olefinic fractions and chemical radicals with unsatisfied valences, these materials being called "residuals." In conventional reforming operations no attempt is made to control the subsequent polymerization of these materials to retain and conserve those desirable anti-knock characteristics and to polymerize the gaseous residuals to liquid hydrocarbons of high anti-knock value.

The principal object of the invention, therefore, is to conserve gases made in reforming operations and to convert them, as by polymerizing and synthesizing, into high anti-knock gasoline-like materials, as well as to convert other gases and liquids to yield similar anti-knock fractions in the gasoline range, whereby polymer gasoline or reformed gasoline or blends of polymer and reformed gasoline are obtained.

The reactions here generically termed "polymerization" include alkylation reactions wherein saturated hydrocarbons react with unsaturated hydrocarbons to form higher molecular weight branched chain hydrocarbons, and alkylation reactions between aromatics and unsaturated low molecular weight hydrocarbons such as ethylene, propene or butene, and straight polymerization reactions wherein olefins such as mono- or di-olefins are polymerized to higher molecular weight polymers. Isomerization, although not strictly a polymerization reaction in the sense that higher molecular weight bodies are formed, is included within this term since it occurs along with such polymerization reactions. The term "polymerization" as here used is intended to embrace these types of reactions for building higher molecular weight bodies by reaction of lower molecular weight hydrocarbons. The gasoline produced by this process is termed "polymer" gasoline, and when produced as a mixture with reformed gasoline it is here termed "reformed and polymer" gasoline. The term "reforming" is intended to embrace the reactions of cracking or decomposition, dehydrogenation and isomerization by which low octane material of gasoline or higher boiling range is converted into gasoline fractions of high anti-knock properties.

This invention seeks to reform gasoline under such conditions that along with the cracking, dehydrogenating and isomerizing operations there will be a parallel, subsequent or conjoint polymerizing reaction where the gases formed in or added to a reforming operation are converted into polymerized materials, whereby a blend of reformed and polymer gasoline of high anti-knock characteristics is formed directly in the process. It is also sought to so treat similar petroleum fractions; also to utilize various gases both saturated and unsaturated, but preferably the latter, obtainable either from the process itself or from other petroleum refining operations; and also to synthesize or polymerize such gases as above mentioned in order to produce therefrom gasoline of high anti-knock qualities.

The invention may be said to reside in one aspect in the reforming of liquid hydrocarbons, particularly hydrocarbons in the gasoline range (although higher boiling range materials also may be employed), for the purpose of producing hydrocarbons having boiling points in the gasoline range but of high anti-knock value and also for the purpose of producing vapors or gases containing hydrocarbons of four or fewer carbon atoms; the vapors being then separately polymerized if desired, or being polymerized in the presence of gasoline fractions produced in the reforming operations, or being partially polymerized separately and then further polymerized in the presence of the gasoline fractions being

produced in the reforming operation. The invention resides further in treating gases or vapors, either saturated or unsaturated, by heating the same under conditions of temperature and pressure so as to effect polymerization, or a modification thereof as by cracking followed by polymerization, accompanied possibly by isomerization of some of the polymerized or modified materials whereby liquid fractions of high anti-knock value are produced. The invention resides also in the addition of hydrocarbons having four or fewer carbon atoms to gasoline to increase the concentration of these low molecular weight hydrocarbons in the gasoline prior to the reforming of the latter.

The process of this invention provides for a controlled polymerization and isomerization of those gaseous residuals and olefins heretofore mentioned, particularly those of the ethylene type, so as to favor continued decomposition of petroleum hydrocarbons and an increased yield of high anti-knock material over that produced from a simple reforming operation. The invention also includes the treatment of liquid fractions by cracking, dehydrogenating and reforming operations to produce materials of high anti-knock value including rearrangement of gasoline-like materials with low anti-knock characteristics and the cracking of higher molecular weight materials to produce lower molecular weight materials with or without parallel operations involving reforming or polymerization including dehydrogenation, whereby high anti-knock liquids are produced. The invention also includes the reforming and polymerization of the normally liquid materials described in the presence of hot cracked products resulting from the cracking of normally gaseous hydrocarbons or kindred light hydrocarbons obtained from a low pressure cracking operation, or from a high pressure cracking operation following low pressure cracking, or from both such operations. The invention also includes the recycling of liquid materials obtained particularly from vapor phase cracking of the liquid stocks to the vapor phase cracking system as well as the recycling in the gas cracking system of liquid materials obtained therein. The control of the treating conditions both in the vapor phase cracking system and in the gas cracking system unit, and the conservation of the residual gaseous materials, involve the recycling of the normally gaseous products from both the gas cracking and vapor phase cracking system, these normally gaseous materials being recycled to the gas cracking system, and preferably by way of an absorption system in which they may be separated from any normally liquid materials associated with them.

As a preferred form, the invention resides in vaporization of normally liquid hydrocarbons preferably under pressure, commingling with said vapors cracked gases resulting from either a low or high pressure cracking operation, or both, followed by subjection of the mixed gases and vapors to treatment in a cracking furnace under pressure whereby polymerization, isomerization and reforming take place. In all instances, the heat treatment is effected under desirable conditions of temperature and pressure to attain the ends desired, and the materials derived from these heat treatments are fractionated in suitable apparatus for the separation and recovery of the materials desired as products and the materials desired for recycling.

The reactions which have been termed "polymerization reaction," and "reforming reaction" are parallel reactions. These reactions are generally reversible, the reaction in one direction being a polymerization reaction, and the reaction in the other direction being a reforming reaction. Consequently, in the polymerization operation and in the reforming operation, all reactions may occur. In general, the polymerization reactions are favored by higher pressures and lower temperatures, while the reforming reactions are favored by lower pressures and higher temperatures; the temperatures and pressures chosen should be those at which the desired reaction predominates. The temperature as well as the pressure will also vary with the feed stock, particularly with its boiling range and the chemical type of the stock and with the pressure. An additional favor is time. The polymerization reactions and decomposition reactions may proceed further by allowing a longer time in the respective portions of the apparatus. Care must be taken to prevent the reforming reaction from going too far, thus forming light, undesirable fractions, or from allowing the polymerization reaction to form undesirable heavy bodies by too long a polymerization time.

Normally gaseous hydrocarbon such as propane, butane, propylene or butylene may be polymerized. Instead of using the hydrocarbons having four or fewer carbon atoms, stabilized or wild natural gasoline containing these fractions may be employed or stabilized or wild similar fractions from various refinery operations. It is in general preferred, however, to use hydrocarbons of the unsaturated type. Sources of such gases are processes in which gas oil and/or fuel oil and the like are cracked at temperatures below about 1000° F., that is, in the neighborhood of 850 to 950° F.

The operations performed upon the normally gaseous hydrocarbons, and the reforming operation employed upon gasoline-like fractions which operation is at least partially a combined cracking, dehydrogenating and isomerizing operation, may be aided by choice of conditions of temperature and pressure and rate of feed, and if desired by selection of catalysts. In general, high temperatures, short time and moderate pressures are desirable. Temperatures may range from 650 to 1850° F. but the range from about 850 to 1200° F. is preferred. Pressures ranging from atmospheric to as high as 3000 lbs. may be employed, but lower pressures, for instance in the neighborhood of 100 up to 1000 lbs. are to be preferred. Reforming or polymerizing catalysts which may be used for the processes herein described will be discussed more fully hereinafter.

In carrying out the process of this invention, the following principles may serve as guides. The feed of liquid fractions preferably has an end point not in excess of 650° F. Usually a heavy gasoline fraction or the like boiling between about 300 to 500° F. will prove satisfactory. However, light gasolines, including straight run gasoline and natural gasoline, both stable and wild, and gasoline-like fractions, both stable and wild, obtained from the recycling gases produced in the cracking operations of the present operations or other cracking operations may be employed. Heavier similar fractions also may be treated. The yield of polymerization products from the treatment of these liquid materials may be increased by adding to the reaction mixture hydro-

carbon materials of five or fewer carbon atoms obtained either from the system itself or from extraneous sources. These may be cracking still gases or gas from any gasoline stabilizing tower in either gaseous or liquefied form. The polymerizing reaction, including addition of unsaturates to unsaturates and alkylation in polymolecular reactions, is favorably influenced by increasing the concentrations of the reactants. This may be accomplished by increasing the pressure, and also by adding materials undergoing polymerization, as by addition of the above mentioned gases to reformed vapors. Such gases are those employed in the gas-cracking and polymerizing operations also here presented.

It is desirable to have present unsaturated hydrocarbons such as butenes, propenes and ethylene. The gases may be obtained from the cracking of gas oil or fuel oil at temperatures from 850 to 1000° F. and preferably, from 900 to 950° F. The gases are those obtained after the cracked gasoline has been removed. Other processes for producing these unsaturates may be employed to produce the unsaturated normally gaseous hydrocarbons here added to the polymerization and reforming operations, as herein described. The saturated normally gaseous hydrocarbons undergo dehydrogenation and polymerization during the reforming operation. The decomposing reactions occur best at low pressures and the polymerization at higher pressures, although there is an overlapping of these reactions in both instances. It, therefore, may be desirable to increase the pressure in passing through the gas polymerization stage. The practical difficulty of compressing hot vapors makes this step difficult, but this may be facilitated by first cooling the vapors, or using a liquid packed surge pump or diaphragm pump or the like, or reducing the pressure differential in some instances. The use of catalysts could be adopted to permit the use of lower pressures for the polymerizing reaction and lower temperatures for the reforming reaction than would be possible without the catalyst.

While the processes of reforming and polymerization are two distinct processes which may be separated the one from the other by careful choice of conditions or catalysts for control of conditions, as previously described, the two processes may be interwoven.

The cracking and dehydrogenating processes of reforming are reversible reactions, and concomitant with them occur polymerizing and hydrogenating reactions. The unsaturated bodies formed as a result of the cracking and dehydrogenation are extremely active and tend to combine with each other. The light unsaturated gases tend to polymerize with themselves and with the unsaturated higher molecular weight bodies present in the reaction zone. It is, therefore, possible to combine the reforming and polymerizing processes and to carry on the polymerization of the lighter fractions (five carbon, and particularly four carbon and lower) in the presence of the hydrocarbons within the gasoline range formed as a result of the reforming operation. By such a combined process, the low molecular weight olefinic products of the reforming processes are continuously and progressively removed by polymerization from the reaction zone as they are formed, thus favoring continued reforming of the petroleum hydrocarbons and an increased yield of high octane material over that resulting from a simple reforming operation. The

lower molecular weight unsaturated hydrocarbons, particularly those of five carbon atoms and less are polymerized with themselves and are also polymerized by addition of the higher molecular weight liquid hydrocarbons of six carbon atoms and more formed in the reforming reaction, or present in the hydrocarbon material forming the charge to the operation.

The process of polymerization and also of reforming results in products including a polymer and reformed gasoline fraction of high octane and having an end point of from 300 to 400° F. depending on operations, a heavy gasoline-kerosene fraction having an end point of about 500 to 550° F. and the like. The heavier fractions such as the "heavy gasoline-kerosene" may be recycled; it will be understood that only a portion may be returned and the remaining portion sent to storage or re-run on blending stock with the polymer and reformed gasoline.

In the accompanying drawings, wherein various systems for practicing the present invention are disclosed by way of illustration—

Fig. 1 is a schematic flow sheet disclosing various units for gas treatment and polymerization by way of gas cracking and for vapor phase cracking, reforming and polymerization both with and without the aid of previously cracked gases;

Fig. 2 is a schematic flow sheet for the polymerization of gases involving gas cracking, polymerization and isomerization including recycling of liquid fractions produced thereby and gaseous fractions; and

Fig. 3 is a similar view disclosing the reforming and polymerization of liquid fractions in which may be involved the use of gaseous materials obtained following low or high pressure gas-cracking or both.

With reference to Fig. 1, major units are indicated by letters. (Corresponding units are employed and similarly indicated in Figs. 2 and 3.) The gas cracking system comprises the low pressure cracking unit or furnace A and the high pressure cracking unit or furnace B, and the vapor phase cracking system comprises the vaporizer C and the cracking, reforming and polymerizing unit or furnace D. These two cracking and polymerizing systems A, B and C, D are provided with fractionating units E and F respectively, by which the cracked, reformed and polymerized materials are separated into gaseous and liquid fractions, the liquid fractions, being designed for recovery and also for recycling where desired. The gaseous fractions are connected for introduction into an absorption system G in which they may be separated into wild and stabilized gasoline and heavier normally gaseous fractions which are returned to the cracking systems A, B and C, D. This absorption system G is also shown as connected to receive and separate other gases, such as natural gas or any saturated or unsaturated refinery gas. In order to indicate sources of suitable materials, an ordinary liquid phase cracking system H is indicated, which produces both liquids and gases, and similarly the crude distillation system K is indicated as producing both liquids and gases. The selected gases are supplied to the gas collecting and feed line 10 and the selected liquids are supplied to the liquid feed line 11.

In connection with the operation of the process as indicated in Fig. 1, the gas for the gas cracking and polymerizing unit A, B is obtained through a gas collecting and feed line 10, and the

liquid material for the vapor phase cracking, reforming and polymerizing unit C, D is received through the liquid collecting or feed line 11. Gases obtained from crude distillation unit K are delivered to feed line 10 through gas header 10a thereof, and those from the liquid phase cracking unit H through the gas header 10b thereof. The crude distillation unit K and the liquid cracking unit H, as indicated, are intended to represent the usual and necessary equipment, such as stills and fractionators, to produce and separate the incident gaseous and liquid products. The crude distillates are collected in tanks 11a connected to supply the liquid feed line 11, and the cracked distillates are collected in tanks 11b, also connected to supply the feed line 11. The normally gaseous hydrocarbons separated by the absorption system G and desired for the present operation are collected in header 10c and delivered to the gas collecting feed line 10. This absorption system G receives gases from the gas cracking system A, B and the vapor phase cracking system C, D through return line 12. The wild and stable liquid gasoline fractions recovered in the tanks 13 and 14, respectively, are connected with the liquid supply line 11. In addition to the gases recycled in line 12 and the gases from the units H and K, other gases such as natural gases and/or other refinery gases saturated or unsaturated may be supplied through lines 10d. If desired, these gases may be passed through the absorption system G or may have been already similarly prepared or otherwise prepared, if required, and introduced directly into the gas collecting and feed line 10.

In the operation of the gas cracking system A, B, the gases are pumped by one of the pumps or compressors P into the heating coils 15 of the furnace A under a pressure which may be anywhere between 0 and 100 lbs. gauge or somewhat higher, preferably between about 30 and 50 lbs., and heated under this relatively low pressure to a cracking temperature between 900 and 1200° F., preferably about 1100° F. This treatment effects the desired low pressure cracking. In normal procedure, the cracked products leaving the coils 15 are conducted by line 16 under influence of compressor pump P' into the cracking coils 17 of the higher pressure cracking and polymerizing furnace B wherein the pressure will be held at any appropriate pressure higher than that in the furnace A such as between 100 and 3000 lbs. gauge, preferably about 1500 lbs., and the temperature is between 900 and 1200° F. preferably about 1050° F., or somewhat below the temperature of the low pressure cracking furnace A. The gases from coil 17 leave the furnace B by way of line 18. If desired, cracked gases from the furnace A may be by-passed around furnace B through line 19 into line 18 or a portion of such gases may be so by-passed and commingled with the high pressure cracked gases leaving coil 17. In either event, the cracked gases are introduced through the line 18 into the fractionating column 20 wherein the pressure is preferably reduced to about 30 lbs. and the materials fractionated at temperatures to produce the desired liquid and gaseous products. The pressures in column 20 may range as high as 300 lbs. according to the pressure conditions in the unit A, B but preferably will be around 30 to 40 lbs. According to one method of procedure, side cuts will be taken from the fractionator 20 through lines 21, 22 and 23 to obtain, respectively, "heavy cycle" stock, "light cycle" stock and "heavy gasoline" for example,

which may be stored in tanks as indicated or withdrawn as products, or recycled to the high pressure cracking furnace B by recycle line 24. The bottoms will be collected, as indicated. The gaseous and vaporous materials from the top of the fractionator 20 will be removed through line 12a, which also acts as a gas header, and may be passed in part directly to the gas recycling line 12 and in part through the cooler 25 or entirely through the cooler 25 to produce a "light gaso-line" supplied by line 26 to a storage tank or draw-off or to recycling line 24. In addition to the recycling of desired liquid products to the high pressure furnace B, uncracked gas may be by-passed through line 27 around furnace A, as for purpose of adjustment of gaseous content or temperature, and fed directly to the furnace B along with the recycled liquid materials, if desired.

In operation of the vapor phase cracking unit C, D, the liquid materials from the liquid feed line 11 are passed through vaporizing coil 30 in the heater C at a temperature of about 800° F. for example, and at a pressure which may be between about 500 and 3000 lbs. gauge, preferably about 1000 lbs. From coil 30, the vapor so produced is passed by line 31 to the cracking, reforming and polymerizing coils 32 in the furnace D where the vapors are heated to a temperature of about 900 to 1200° F. but preferably at about 1025° F. under a pressure between about 500 and 3000 lbs., preferably around 700 lbs. or somewhat lower than the pressure in the vaporizer C. According to one phase of the invention only a vaporized material from the coil 30 will be treated in the coils 32 but according to another phase of the invention cracked gases from the gas cracking unit A, B will be introduced by way of a cracked gas line 33 into the vapors passing through the line 31 to the coil 32, whereby the reformation of the vaporous materials and the polymerization of the mixed materials, both gases and vapors will be facilitated. The cracked gaseous materials supplied from the gas cracking system A, B may be taken either from the line 16 through branch 33a as they leave the furnace A, or from the line 18 through branch 33b as they leave the furnace B, or they may be obtained as a mixture of low pressure and high pressure cracked gases collected through both branches 33a and 33b of the line 33. It is to be understood that in all cases the necessary pumps and valves and like equipment will be employed to effect the necessary passage of gases, liquids and vapors and to attain the pressures required.

Thus, where working at the high temperatures indicated, in order to raise the materials from furnace A to the desired pressures in furnaces B and D, it may be necessary in practice either to cool the cracked products before they enter the compressor or to use a diaphragm pump or a surge pump using a liquid body ahead of the piston as a gas-contacting medium. Or the pressure in the furnace A may be raised somewhat higher than above stated by the cool feed-gas pump and thereby correspondingly reduce the operating differential when such higher pressure will permit the desired effects in furnace A.

The cracked and polymerized materials leaving the coil 32 of furnace D are then passed by way of line 34 to a fractionator 35 in the unit F corresponding to the fractionator 20 in the unit E wherein the desired liquid fractions are obtained as side cuts in the form of "heavy cycle," "light cycle," and "heavy gasoline," these materials be-

ing drawn through lines 36, 37 and 38, respectively, to corresponding storage tanks or draw-offs and being also connected with a line 39 for recycling to the inlet side of the coil 30 of vaporizer 30. Bottoms may be drawn off through storage tank and/or connected through line 40 for recycling by way of line 39. Gases and vapors from the top of this fractionator 35 are drawn through line 12b which also constitutes a gas header receiving liberated gases also from the liquid side cuts through line 42, and introduced in part, if desired, into gas recycling line 12, and at least in part through cooler 43 or entirely through cooler 43 to yield a "light gasoline" liquid fraction which is passed by way of line 44 to storage or recycled, if required, through line 39.

As indicated, all gases from the various elements of the fractionating units E and F are returned to the gas recycling line 12, and passed thence preferably through the absorption system G. Here the gases pass upward through absorber 50 against a descending stream of lean absorption oil fed into the top of absorber 50 through line 51. The dry gases leaving the top of absorber 50 will be chiefly methane containing a quantity of ethane and ethylene and any hydrogen present. According to present operating procedure, these gases are too light for satisfactory use and are vented from the system through line 52. The rich absorption oil withdrawn from the bottom of absorber 50 through line 53 is discharged into still 54 wherein the absorbed heavier constituents of the gas are distilled off, the lean oil being withdrawn from the bottom and returned through line 51 (following proper cooling). The gases and vapors from the top of still 54 are then passed through cooler 55 to condense out unstable gasoline-like materials which are passed through line 56 to storage 57 and thence to stabilizer 58. The stabilized gasoline is withdrawn into container 14 connected with liquid collecting line 11 feeding to the vapor phase cracking unit C, D. The wild materials from stabilizer 58 are passed through cooler 59 and the condensed constituents are passed by line 60 to the wild gasoline container 19 also connected with liquid feed line 10. In order to conserve the uncondensed gaseous materials from the coolers 55 and 59 and from the containers 13, 14 and 57 suitable connections as shown are made with the gas header 10c leading to the gas collecting line 10. If desired, valved lines such as 61 and 62, may be employed for injection into gas header 10c of light fractions from the top of absorber 50 or of fractions from the top of the still 54 should it be necessary or desirable to inject any of these materials into the gas stream supplying the gas cracking unit A, B.

In Figs. 2 and 3, preferred methods of procedure are indicated, employing the same units as shown in Fig. 1.

Fig. 2 discloses a preferred method of cracking and polymerizing normally gaseous hydrocarbons supplied from the feed line 10 as in Fig. 1. Here the gas cracking unit A, B consists of the low pressure cracking furnace A containing the low pressure cracking coil 15 operated at temperatures and pressures previously defined for Fig. 1, the resultant cracked gases being passed to the high pressure cracking coil 17 in the furnace B and subjected to cracking, polymerization and isomerization operations under pressure and temperature conditions previously described in connection with Fig. 1, the cracked products leaving the coil 17 through cracked gas line 18. 75

Cracked gases from the coil 15 may be by-passed from line 16 around furnace B and into the discharge line 18 from furnace B for the purpose of direct fractionation of the low pressure cracked gases without subjecting them to the high pressure operation, or for the purpose of subsequently fractionating a mixture of low pressure cracked gases and high pressure cracked gases.

From the discharge line 18, the cracked products are passed into the fractionating system E (which is intended to be the same fractionating system E as disclosed in Fig. 1), wherein they are separated into gases fed to the recycling line 12 and into liquid products which are indicated respectively as "heavy cycle" material, "light cycle" material, "heavy gasoline" and "light gasoline," and pass through the lines 21, 22, 23 and 26 either for separate recovery or for recycling by way of line 24 to the high pressure cracking and polymerizing furnace B. The gases 12 are conducted to the absorption system G for separation into light dry gases which may be vented through the line 52 as previously described, and heavier normally gaseous hydrocarbons which are returned through the absorption gas manifold 10c to the primary gas feed line 10. The absorption system G, as here represented, is intended to be the same as that disclosed in Fig. 1 and in it are produced wild and stable gasoline fractions which are respectively collected in tanks 13 and 14 for other uses. Feed gas may be bypassed around furnace A through line 21, as for purpose of temperature control, for example, or adjustment of content.

Thus, according to Fig. 2, various gases, but preferably unsaturated gases of the butene, propane and ethylene types, are cracked or dehydrogenated at temperatures preferably around 1100° F. and at pressures around 30-50 pounds and are then passed into the high pressure cracking and polymerizing device B where they are treated at pressures preferably around 1500 pounds and temperatures around 1050° F. to effect polymerization of the materials obtained from low pressure furnace A, the operation being also accompanied by isomerization of materials whereby fractions are produced which, when condensed in system E, will yield, among others, desirable liquid gasoline-like materials of high anti-knock value. This invention also contemplates the bypassing of gas from the low pressure cracking unit A around the unit B either for separate treatment in the fractionating system E or for commingling with the high pressure cracked materials from coil 17, in furnace B. In the latter instance where the materials are commingled, a certain amount of increased polymerization or desirable control may sometimes be effected as the starting materials vary.

In order to modify or control the operations in the furnace B, and sometimes in order to produce further materials in the gasoline range, various liquids obtained from fractionating system E may be recycled to the feed side of furnace B through line 24. Thus, by recycling of the intermediate or heavy gasoline fractions, further polymerization or isomerization may be effected together with reforming operations, and by recycling heavier materials, such as cycle stock, further cracking and reforming thereof may be effected for the production of additional desired high anti-knock liquids in the gasoline range. For purposes of further control, gases may be introduced directly from the feed line 10 to the furnace B by way of line 27 either with or without

out the recycling liquid materials. Thus, certain gases, such as propylene and butylene and sometimes propane and butane when mixed with the materials in the furnace B, are subject to direct polymerization.

As to the reactions in the gas cracking unit A, B, the lower pressure in furnace A fundamentally favors cracking, but we find many activated molecules which polymerize in this zone to normally liquid materials. Similarly, the high pressure in furnace B favors polymerization of the cracked materials from furnace A, but here again we have overlapping reactions taking place at the high operating temperatures and some cracking therefore occurs in this zone also. As a result both reactions take place to some extent in both zones.

In the operations indicated in Fig. 3, reforming of gasoline-like materials entering through the feed line 11 is combined with and takes place in the presence of cracked or dehydrogenated gases, or of cracked and polymerized or isomerized gases obtained from cracking unit A, B. Thus, the liquid feed stock entering through line 11 passes to the vaporizing coil 30 in vaporizing furnace C and thence by line 31 to the reforming and polymerizing coils 32 in furnace B. Gases obtained through the gas feed line 10 are treated in a low pressure cracking coil 15 of furnace A under conditions above described for the other figures and may be passed therefrom through line 16 into the high pressure cracking coils 17 of furnace B for polymerization and isomerization. Treated gases either from coil 15 of furnace A or from coils 17 of furnace B or mixtures of these, may be passed through cracked gas line 33, including its branches 33a and 33b, into the vapors passing through line 34 from vaporizer C to polymerizer D. A quantity of feed gas may be by-passed to line 33 through by-pass 21, if required. In the coils 32 of the furnace D, the cracked gases from the cracking unit A, B or from the unit A alone, undergo polymerization in the presence of the vapors from the vaporizer C which are being reformed and polymerized in the same coils.

These reactions between the two types of materials (vapors and cracked gases) taking place in the presence of each other result in the production of a high percentage of highly valuable anti-knock gasoline-like materials which are passed through the line 34 into the fractionation system F (being the same as the system F of Fig. 1), wherein the liquid materials are condensed, fractionated and separated from the gases to produce a series of cracked liquids in the form of bottoms, heavy cycle stock, light cycle stock, heavy gasoline and light gasoline which are respectively passed through lines 36, 37, 38 and 44, either for recovery of the liquid materials through the valved discharge lines shown or for recycling to the vaporizer C by way of recycling line 39. Particularly the cycle stocks and the heavy gasoline may be so recycled.

The vapors and gases delivered from the fractionating system through the manifold 12b are passed by way of gas return line 12 to the absorption system G (above described) whence they are separated into gaseous materials returned by way of the absorption gas manifold 10c to the main gas feed line 10, the dry gases of the ethane or methane type previously described being preferably vented through the vent line 52. The liquid materials from the absorption system G are collected as wild and stable gasoline in the condensers 13 and 14 either for separate recovery or

for recycling to the liquid feed line 11 as by way of the recycling line 39.

Referring to Figs. 1 and 3, it is within the scope of this invention to operate so that, instead of treating in the furnace C to effect principally vaporization or incipient cracking, this furnace may be operated to vaporize and then produce substantial cracking or to vaporize and then form cracked materials primarily. In this manner, the operation in polymerizing furnace D will result in less cracking and be more distinctly a polymerization and isomerization of products produced in furnace C. Thus, it will be desirable, according to this form of the invention to use relatively high temperatures in the reforming or cracking zone C and preferably lower pressures relative to the furnace D, and then in any desired manner to cool the reaction products produced by the dehydrogenating and cracking reactions in zone C before passing them to the polymerizing zone D. As an example, the cracking or reforming furnace C may be carried at pressures of from 500 to 1000 lbs. and at temperatures around 1000 to 1100° F., and the polymerizing furnace D may be carried at pressures of 1200 or 1500 lbs. up to around 3000 lbs. and at temperatures preferably somewhat lower than the temperatures in zone C, for example 950 to 1050° F. Thus, the relatively higher pressure and relatively lower temperature in zone D will facilitate polymerization of the materials from zone C or of mixed materials from zone C and gas treating unit A, B. Materials in the heavy gasoline-gas oil range may be used for this purpose. The yield of polymerization products is increased by adding to the reaction materials from cracking zone C hydrocarbons of five or fewer carbon atoms, such as obtained through the line 33 from the gas treating unit A, B as previously described, or even by introduction of gases (in gaseous or liquid form) from the gas feed line 10 by way of by-pass 21 as illustrated in Fig. 3. This addition of gases includes the addition of unsaturates to unsaturates and the addition of saturates to unsaturates. Alkylation in poly-molecular reactions is increased by this concentration of the reactants.

As to the distinction between the normally gaseous hydrocarbons which are to be vented from the system and which are to be returned to the gas cracking units, according to present operations, it is preferred to vent from the system all or substantially all of the unabsorbed gases from the absorption system, these consisting principally of the methane and a quantity of the ethane and ethylene. The remaining ethane and ethylene do not separate from the propane, butane, propylene and butylene and pass into the absorption oil along with the heavier constituents, which find their way through the absorption oil still 54 back into the gas feed line 10c. The cut between the gases may be controlled in any desired manner by regulation of temperatures and pressures, and if quantities of the lightest materials are desired in the gas cracking system, some of these may be retained so long as overloading with light materials is avoided by adequate venting, as will be apparent to the skilled operator. If dehydrogenation catalysts are used, as herein-after discussed, the volume of hydrogen to be vented will, of course, be considerable.

From the foregoing, it will be apparent that we have presented operative procedures for the conversion of various types of normally gaseous hydrocarbons, both of saturated and unsaturated

character, into normally liquid gasoline-like fractions of high anti-knock value. Thereby we have not only produced materials valuable in the industry, but we have also presented a means for conserving a large quantity of the low molecular weight hydrocarbons which have heretofore found no use other than as gaseous fuel or the like. At the same time we have presented a means for reforming liquid fractions, such as those in the gasoline range, especially in the presence of normally gaseous constituents preferably cracked and/or polymerized and/or isomerized, whereby reforming of the gasoline-like fractions and polymerization and isomerization of vaporous and gaseous materials take place under conditions where such vapors and gases are in the presence of each other and the resulting liquid products obtained in commercially high percentages and have desirably high anti-knock characteristics.

The invention as generally disclosed above is intended to be operated without the use of catalysts. However, as has been suggested, catalysts may be employed in connection with the various steps. Reforming catalysts which have been found useful for this purpose are: *Metals*.—Nickel, palladium, platinum, copper, cobalt, iron, zinc, titanium, aluminum, tungsten, molybdenum, thorium; *Sulfides*.—Cobalt, iron, zinc, nickel, manganese, tungsten; *Oxides*.—Alkali metals such as calcium, magnesium, thorium, titanium, iron, uranium, barium, aluminum, chromium, zinc, nickel, manganese and particularly manganese peroxide, silica; *Hydroxides*.—Chromium, alkali metal; *Acids*.—Molybdic, tungstic, chromic, phosphoric, arsenious, silica, boric; *Salts*.—Aluminates, chromates, tungstates, vanadates, uranates, phosphates, of the alkali earth metals such as calcium and the alkali metals, i. e. potassium, for instance potassium chromate, dichromate, chromite and dichromite; and the phosphates, chromates and vanadates of aluminum, chromium or zinc; phosphates of molybdenum, tungsten; borax, ammonium molybdate, aluminum sulfate; adsorbents like fuller's earth, bentonite; *Adsorbent charcoal* or other adsorbent carbons; *Halides*.—Such as aluminum chloride, iron chloride, aluminum bromide and iron bromide. Another appropriate catalyst is that formed by coating alumundum or absorbent clay or charcoal or silica gel with potassium chromate and zinc sulfate, drying and heating in a stream of hydrogen. Also selenium vapors may be used.

When hydrocarbon fractions having a boiling range up to about 600-650° F. are passed over these catalysts at temperatures from 662-1832° F. a reforming reaction occurs. In producing gasoline containing olefinic materials temperatures of about 850-1050° F. may be employed. Higher temperatures in the neighborhood of 1380-1830° F. favor aromatic formation. The salts and oxides of the difficultly reducible metals; as for instance, the alkali metals such as calcium, magnesium, barium, require in general higher temperatures for the formation of olefins, i. e. temperatures in the neighborhood of 1020-1380° F. The gases resulting may then be reacted in the presence of a polymerizing catalyst.

Catalysts which have been found to aid polymerization are termed "polymerizing catalysts." Such catalysts are fuller's earth, absorbent carbon, phosphorous acids such as orthophosphorous acid, and phosphoric acid such as ortho-

phosphoric acid in solid form, aluminum oxide, calcium oxide, carbonates of the alkaline metals, the oxides and carbonates of magnesium or beryllium, the acids of boron and antimony, 5 thoria, zinc chloride or aluminum chloride, cadmium phosphate, aluminum sulfate in solid form, adsorbent clays like bentonite, graphite, charcoal, copper, alkali metal salts (especially oxygen-containing salts), phosphates, borates, antimonates, boron trifluoride, either alone or as a double compound with ethylene in the form of ethylene fluoboric acid, cadmium phosphate, and siliceous earths, tin, zinc, aluminum, chromium, silicon, lead or alloys of these metals.

10 15 In using the reforming and polymerizing catalysts, one skilled in the art will understand that the conventional methods of preparing catalysts of this nature are to be followed. Thus, the metals are best used when in finely divided form and better when supported on carriers. The clays such as bentonite and fuller's earth are best used in their activated states, thus fuller's earth is used in the acid treated state, in which state their adsorptive activity is best brought out.

20 25 Methods of increasing the adsorptive activity of clays and adsorbent carbon are well known in the adsorption art.

30 In using catalysts to be carried in the stream of gases, the catalyst, if it is boron fluoride, may be fed as a gas to this stream or mixed in the liquid state at low temperature. Selenium vapors may be similarly introduced. If the catalysts are solid they are best ground fine and carried in suspension by mixing with the liquid feed and carried along by the high velocity of the vapors. The solid catalyst may also be positioned as a contact mass in the reaction zone and the vapors passed through the body of catalyst.

35 40 Various catalysts promote one or the other reactions, favorably, under certain temperature conditions. The temperatures and pressures herein disclosed are merely illustrative and are those at which the various reactions predominate, but the opposite reaction, whether it be reforming or polymerization, also occurs. The temperatures are merely illustrative and are for feed stocks as herein described, and for pressures from atmospheric to 5000 lbs.

45 50 Thus, with metal catalysts, tin, zinc, copper, aluminum, chromium, silicon, lead and nickel favor polymerization reactions in the temperature range between 350 and 700° F.

Catalytic oxides used for these reactions, such 55 as aluminum oxide either alone or combined with silica in the form of aluminum silicates, for instance, floridin or fuller's earth, favor polymerization in the temperature range between 570 and 750° F. Preferably, aluminum oxide should be used in the neighborhood of from 640 to 700° F. Lime and other alkali earths or oxides or carbonates favor polymerization in the range between 660° F. and 840° F. Magnesium and beryllium oxides favor polymerization reactions in the upper part of said range around 840° F. to 930° F. Aluminum chloride and boron trifluoride are very active at temperatures from 32° F. to 300 or 390° F. Magnesium oxide, lime and silica, such as silica gel, can be used in reforming reactions in temperature ranges above 930-1290° F. Aluminum oxide or aluminum silicate such as fuller's earth or floridin or other forms will favor reforming above 750° F. Thus in using aluminum oxide, either alone or in the form of silicate, the temperature ranges should be adjusted depend-

ing on the form of the reaction which is to be favored. In operating in the upper ranges around 750° F. aluminum oxide will have a favorable influence on both reactions, aiding in the decomposition in the higher molecular weight liquid hydrocarbons, and aiding in the lower molecular weight gaseous hydrocarbons. The temperature range should be chosen to form a balance between the two.

Of the salts or adsorbents which accelerate polymerization reaction, the alkali metal carbonates, phosphates and borates are active in the neighborhood of 750-930° F.; bentonite is active from 660-840° F.; phosphoric acid is active from 350-475° F. Absorbent charcoals and carbons favor the polymerization reaction at around 750° F. Above those temperatures, and particularly at substantially higher temperatures reforming is favored by these catalysts. Calcium aluminate, ammonium molybdate favor the reforming operations at temperatures of 930-1290° F. and higher. Aluminum sulfate and phosphoric acid are active in reforming reactions above 660° F. and very active above 930° F.

Mixed catalysts composed of mixtures of any one or more of the above reforming catalysts, and any one or more of the above polymerizing catalysts, which are active, i. e. promote and accelerate the reforming and polymerizing operation in the neighborhood of 700-930° F. will permit of the joint and favorable reactions of reforming and polymerization when operated at temperatures between about 700-930° F. at pressures of about 75-1500 lbs.

A good catalyst for the polymerization reaction is aluminum oxide preferably in the form of fuller's earth or artificial fuller's earth formed by co-precipitating silica and aluminum oxide from a mixture of sodium silicate and aluminum sulfate. The aluminum silicate is washed neutral and dehydrated. It is preferred that the mixture be neutral or acid, and free of alkaline material. It is best that the catalyst be substantially free from water, dehydrated by heating, although a small percentage, up to 5 or 6% of moisture is not detrimental. In using this catalyst it has been found that a small amount of hydrochloric acid introduced as alkyl chloride, as for instance, isopropyl chloride may be introduced to aid the polymerization reaction. Apparently, the isopropyl chloride is decomposed in the reaction zone and forms free hydrochloric acid.

It has been found that the alkyl chlorides are conveniently formed by passing a mixture of unsaturated hydrocarbons such as butylene and propylene over the above fuller's earth type catalysts as previously disclosed at ordinary temperatures from about 200-400° F. The alkyl chloride may be introduced either in vapor form as produced by the chlorinating reaction, or first condensed, and then introduced in liquid form. The amount of alkyl chloride required varies from one-tenth to one per cent, preferably to about one-half percent of the reaction vapors.

The catalysts here employed may be used in the reforming or polymerizing processes either as a catalyst body or as a mixture with incoming feed. In using the catalyst as a catalyst body, the reaction zone in the tube or chamber is charged with the solid catalyst and the reaction vapors are passed through the body of the cata-

lyst. It is possible, however, to use the catalyst as a slurry with the incoming feed, in which case the reaction zones are empty except for the reaction mixture. When the vaporized hydrocarbons carrying the catalyst ground fine in suspension pass through the reaction zone, the high velocity of the vapors and the fine particle size of the catalyst prevent sedimentation of the catalyst in the tubes or chambers.

The foregoing description of the several modifications of our invention described above are not to be considered as limiting since many variations may be made within the scope of the following claims by those skilled in the art without departing from the spirit thereof.

We claim:

1. A method for the conversion of hydrocarbon gases and liquids into gasoline-like fractions having high anti-knock characteristics comprising subjecting a normally gaseous hydrocarbon to cracking conditions, subsequently subjecting a portion of such cracked gases to higher pressures to effect polymerization of said gases, commingling the products of said polymerization with normally liquid petroleum hydrocarbons and with the remaining portion of cracked gases, passing said mixture of products of polymerization and added hydrocarbons into a heated cracking and polymerizing zone under substantial pressures and effecting reforming of said added hydrocarbons and polymerization of the mixed materials, and fractionating the products to yield normally liquid materials in the gasoline range.

2. A method for the conversion of hydrocarbon gases and liquids into gasoline-like fractions having anti-knock characteristics comprising subjecting a normally gaseous hydrocarbon to cracking conditions, subsequently subjecting a portion of such cracked gases to higher pressures to effect polymerization of said gases, commingling the products of said polymerization with gasoline hydrocarbons and with the remaining portion of cracked gases, passing said mixture of products of polymerization and added hydrocarbons into a heated cracking and polymerizing zone under substantial pressures and effecting reforming of said added hydrocarbons and polymerization of the mixed materials, and fractionating the products to yield normally liquid materials in the gasoline range.

3. A method for the conversion of hydrocarbon gases and liquids into gasoline-like fractions having high anti-knock characteristics comprising subjecting a normally gaseous hydrocarbon to cracking at temperatures in the neighborhood of 1000-1100° F., subsequently subjecting a portion of such cracked gases to higher pressures to effect polymerization of said gases, commingling the products of said polymerization with normally liquid petroleum hydrocarbons and with the remaining portion of cracked gases, passing said mixture of products of polymerization and added hydrocarbons into a heating cracking and polymerizing zone under pressures above about 1000 pounds and effecting reforming of said added hydrocarbons and polymerization of the mixed materials, and fractionating the products to yield normally liquid materials in the gasoline range.
